The Gardner-Richardson Company, Middle-
town, Ohio, a corporation of Ohio

Application July 7, 1939, Serial No. 283,230

16 Claims. (Cl. 91—51)

This invention relates to paper making and more particularly to the provision of a surface coating on a web of paper material.

A principal object of the invention is to provide a paper web having a greasewood surface coating applied thereon under controlled conditions as a homogeneous film having substantially uniform and predetermined density across the entire width and along the entire length of the paper web.

A further object is to provide a process for applying to a paper web a coating of surfacing material having a volatile constituent such as a volatile solvent adapted to be lost by evaporation and to obtain controlled retention of such volatile constituent during the coating operation to provide for maintaining predetermined viscosity characteristics in the coating composition and effecting the application of a coating film of the desired thinness and uniformity.

A further object is to provide such a process for coating a paper web which makes it possible to apply a generally uniform coating film to the sheet and hence secure a high degree of economy in the use of the coating composition.

A still further object is the provision of relatively simple and inexpensive apparatus for applying such uniform thin film of surface coating material to a web of paper.

Other objects and advantages will be apparent from the following description, the appended claims and the accompanying drawings in which:

Fig. 1 is a diagrammatic elevational view illustrating the general layout of the apparatus employed in the present invention;

Fig. 2 is a plan view with the upper press roll removed of a coating machine constructed in accordance with the present invention;

Fig. 3 is an end elevational view taken interiorly of the end frame of the coating machine as indicated by the line 3—3 of Fig. 2;

Fig. 4 is a sectional view taken on the line 4—4 of Fig. 2;

Fig. 5 is a fragmentary detail view of a portion of the doctor blades at the forward side of the machine; and

Fig. 6 is a fragmentary elevational view taken at one end of the machine and showing the adjustable doctor blade at the rear of the machine in detail.

The present invention provides for maintaining continuous control over the characteristics of the coating composition as regards solvent content, viscosity and the like, to effect its application to the paper web in a uniform thin film hav-

ing controlled viscosity and volatile content. The invention is of particular importance in the case of a coating material having a volatile solvent as one of its constituents, such, for example, as in the case of a nitrocellulose coating where it is customary to make use of a mixture of highly volatile solvents such as acetone, methanol, gasoline and/or toluol. With such coating materials it has been found that if the coating material is merely applied to the paper web by means of nip rolls dipping into a relatively large exposed pool of such material, the composition tends to lose a substantial portion of the volatile solvent by evaporation. Under these conditions the composition becomes more and more viscous with the passing of time and a heavier coating film is applied. Furthermore, if the relatively thin film of coating material which is picked up on the surface of the pick-up roll dipping within the pool is exposed to contact with the atmosphere between the time that it leaves the pool and the time that it is applied to the paper web a further evaporation of the volatile solvent occurs with a corresponding change in the viscosity of the film. These changes in the viscosity of the coating material due to the loss of the volatile solvent therefrom not only result in a substantial decrease in the amount of coverage which can be obtained with a given quantity of the material, but also result in the application of the coating material to the paper web in a non-uniform film having a density which is variable across the width of the web and which is subject to change along the length thereof.

In accordance with the present invention only so much of the coating material is supplied to the coating apparatus which applies it to the paper web as will be used up in a relatively short period of time and the conditions under which the coating material is applied to the web are so controlled as to substantially avoid free contact of the material with atmospheric air from the time that the material is introduced into the coating apparatus until after it has been applied to the paper web. A fresh quantity of the coating material is supplied to the apparatus only when the material already therein has been substantially used up and this fresh supply is introduced in such manner as to cause the material which remains in the bottom of the apparatus to be flushed or washed into a position where it will be picked up and applied to the web of paper. In this manner the use of dominant pools which tend to retain a portion of the coating material is avoided and a fresh coating material having a

predetermined constant volatile content and viscosity is applied to the paper web at all times. Since a given quantity of coating material remains in the coating apparatus for only a relatively short period of time and since the coating material in the apparatus is maintained substantially free from contact with the atmosphere until after it has been applied to the paper web any substantial loss of the volatile solvent is avoided and the coating is applied to the paper web in a film of satisfactory uniformity both transversely and lengthwise of the web. This uniformity of coating makes it possible to secure a marked economy in the use of the coating composition, since it is not necessary to apply an excess to parts of the web in order to secure sufficient depth of film over the entire web.

Referring now to the drawings which illustrate a preferred embodiment of the invention, and more particularly to Figs. 2 to 4, the coating machine designated generally by the reference character 10 is shown as comprising a pair of vertically arranged press rolls 11 and 12 mounted on suitable shafts rotatably supported in end frames 13 and 14. Only the shaft 15 for the lower press roll 12 is shown in the drawings. A paper web 17 from any suitable source is fed to the press rolls in the direction of the arrow in Fig. 4 and the coating of surfacing material is applied to the under side of the web as it passes through the nip of the rolls. The bearings for the upper roll 11 are preferably adjustable in the end frames 13 and 14 to provide for receiving different thicknesses of paper material between the rolls, and suitable means such as adjustable springs or the like may be provided for effecting a desired pressure between the two rolls. A suitable drive means (not shown) is also provided for effecting rotation of the press rolls in the direction indicated by the arrows in Fig. 4.

A fountain or tank member 20 adapted to receive a predetermined limited quantity of the surfacing material therein is supported between the frame members 13 and 14 as indicated at 21 and provides for continuously supplying the coating material to the surface of the lower press roll 12. As best shown in Fig. 4 the fountain 20 comprises an arcuately curved front side wall 25, an arcuately curved rear side wall 26 and an arcuately curved bottom wall 27. The curved wall portions 25, 26 and 27 are arranged concentrically with the axis of the lower press roll 12 and are positioned relatively close to the periphery of the lower roll to provide only a predetermined limited space between the inside of the fountain and the outer surface of the press roll. To provide an even more limited space between the press roll and the bottom of the fountain where the coating material is picked up the bottom wall portion 27 has a smaller radius of curvature than the side wall portions 25 and 26 to position the bottom wall portion closer to the press roll as is clearly shown in Fig. 4. Suitable spacing members 28 and 29 are provided between the bottom wall portion 27 and the respective side wall portions 25 and 26 and are welded or otherwise imperviously attached to the respective portions of the wall.

The front wall portion 25 adjacent its upper end is bent outwardly and upwardly to provide an upwardly inclined ledge 32 and an upstanding portion 33. A door 34 having transparent windows 35 and handles 36 extends across the entire length of the fountain and is hingedly at-

tached to the upstanding portion 33 of the front wall 25 as is indicated at 37. Handles 36 and hinges 37 provide for readily swinging the door 34 outwardly to provide ready access to the nip of the rolls for the feeding of a new web of paper thereto or other purpose. Suitable stops provided on the end plates of the fountain limit movement of the door 35 towards the press rolls to substantially the position shown in Fig. 4. The door extends upwardly to above a horizontal plane passing through the nip of the press rolls and is provided at its upper end with a horizontally projecting flap 38 which extends into close juxtaposition to the upper press roll 11. The flap 38 is attached to door 34 by means of spring hinges 39 which normally maintain the flap in a substantially horizontal position as shown but permit the flap to swing downwardly in the event of some obstruction on the roll or paper web striking the same. The paper web 17 is fed to the nip of the press rolls through the relatively small spacing provided between the end of the flap 38 and the upper roll 11. The door 34 and flap 38 thus substantially enclose the interior of the fountain and the nip of the press rolls at the forward side of the machine and thereby avoid substantial contact of the coating material, either in the fountain or when on the surface of pick-up roll 12, with the atmosphere at this side of the machine.

A back cover member 42 having a radius of curvature similar to the rear wall portion 26 of the fountain is hingedly mounted on the wall portion 26 as indicated at 43 and is provided at its upper end with an inwardly projecting flange 44 which extends into close proximity to the periphery of the lower press roll 12. Handles 45 provide for swinging the back cover member 42 to an open position when it is desired to have access to the lower press roll, and suitable stops provided on the end plates of the fountain limit movement of the cover 42 and flange 44 towards the lower roll when the cover is in closed position. The door 34 and flap 38 at the forward side of the machine and the back cover 42 and flange 44 at the rear side of the machine thus provide for substantially enclosing the interior of the fountain and the entire surface of the lower roll 12 to thereby avoid substantial contact of the coating material with the atmosphere until after such material has been applied to the paper web at the nip of the press rolls and has passed outwardly from the machine.

The fountain 20 is closed at each end by means of a lower end plate 48 and an upper removable end plate 49. The lower end plate 48 is substantially semi-circular in shape and is permanently attached to the side and bottom wall portions 25, 26 and 27 of the fountain. The upper removable end plate 49 rests upon the top of the lower plate 48 and has a shape generally corresponding to the contour of the upper portion of the fountain. As shown in Figs. 2 and 3 the end plates 48 and 49 are provided with cooperating notched flanges 50 and 51 at their line of junction, and toggle screws 52 pivotally mounted on the upper end plate and having nuts 53 adapted to engage the lower flanges 50 are received within the notches 54 of the flanges and provide for removably clamping the upper end plate 49 to the lower fixed end plate 48. The upper removable end plate 49 is so constructed as to have a tight fit with the ends of the main body portions of the fountain, and the end walls of the fountain are positioned relatively close to the ends of the

press rolls to thus substantially prevent the leakage of air into the interior of the fountain and escape of the volatile solvents therefrom.

The inclined ledge 32 on the front wall portion of the fountain provides a support for the doctor blades which are provided at the forward side of the machine to control the quantity of coating material transferred to the paper web at the nip of the press rolls. As shown in Figs. 3, 4 and 5 the doctor at this side of the machine comprises a plurality of adjustable doctor blades 60 which are mounted in predetermined spaced positions along the length of the press roll 12 and a plurality of fixed doctor blades 61 which extend along the length of roll 12 between the adjustable doctor blades 60. The fixed doctor blades 61 are rigidly attached to the ledge 32 by means of screws 62 (Fig. 3) which extend through elongated slots 63 provided in the doctor blades and thread into tapped openings provided in the ledge. These fixed doctor blades are adapted to extend forwardly into contact with the lower press roll 12 and provide for scraping substantially all the coating material from the portions of the outer surface of the lower roll which come in contact therewith. The elongated slots 63 provide for an initial adjustment of the doctor blades 61 to effect such contact between the doctor blades and the press roll, after which the holding screws 62 are tightened and the blades are maintained fixed in this positioning.

The adjustable doctor blades 60 are adapted to be moved towards and away from the lower press roll 12 to provide for controlling the quantity of coating material that is carried upwardly by the surface of the roll to be applied to the paper web and for limiting it to a plurality of spaced bands which distribute into a continuous pool extending across the entire nip of the rolls. As shown in Fig. 4 the ledge 32 is provided with an elongated opening 65 at each position of the adjustable doctor blades and a slide block 66 attached to the doctor blades by the screws 67 is slidably received within this opening. A thumb screw 68 journaled in depending flanges 69 provided on the ledge 32 and having threaded engagement with the slide block 66 provides for moving the slide block within the opening 65 to effect the desired adjustment of the end of the doctor blade relative to the outer surface of the roll 11. A collar 70 and set screw 71 cooperate with the knurled head 72 of the thumb screw and the flange 69 to maintain the thumb screw in fixed axial positioning with respect to the ledge 32.

To provide a machine that is adapted to receive paper webs of different widths the press rolls 11 and 12 are made of considerable length and an adjustable doctor blade 75 is provided adjacent each end of the machine for scraping the coating material from the portions of the upper roll 11 which extend beyond the edge of the paper web. As shown in Figs. 2, 4 and 6 an inverted channel member 76 is welded to the overhanging flange 44 of the rear cover member 42 adjacent each end of the machine and the doctor blades 75 are mounted on this channel member by means of thumb screws 77 which extends through elongated slots 78 provided in the doctor blade and thread into tapped openings 79 provided in the top of the channel member. The elongated slots 78 extend substantially parallel with the axes of the feed rolls and provide for limited axial adjustment of the doctor blade towards the side edge of the paper web 17 received between the rolls. The channel member is provided with

5 a relatively large number of tapped openings 79 and if a greater adjustment of the doctor blade is required the thumb screw 77 can be entirely removed from one set of openings and threaded into a different set. It has been found in practice that satisfactory operation is obtained when the doctor blades 75 are adjusted to a positioning in which they are spaced approximately one-fourth of an inch from the side edges of the paper web. The doctors extend forwardly of the channel support and the flange 44 into engagement with the upper roll 11 and in overhanging relation with respect to the lower roll 12. Thus as the rolls rotate any of the coating material which may have been transferred to the surface of the upper roll is scraped off by the doctor blades and falls upon the lower roll where it is carried back into the apparatus for further application to the paper web.

10 As mentioned above only a predetermined limited quantity of coating material such as will be used up within a relatively short period of time is supplied to the machine at any one time. The coating material is introduced into the fountain 20 through a pair of nipples 82 which are mounted in the rear wall portion 26 of the fountain adjacent each end of the coating machine and connect with a supply source positioned externally of the machine. Referring to the diagrammatic layout of Fig. 1 a large supply tank 85 is positioned in a desired safe location under the ground and is provided with a pipe 86 for filling the tank with the coating material and a pipe 87 for withdrawing the coating material from the tank. The pipe 87 connects with the suction side of a pump 88 driven by an electric motor 89 and the discharge side of the pump is connected to a pipe 90 which extends from the pump to the coating apparatus 10 and is provided with branch pipes 91 and 92 which connect with the nipples 82 mounted in the wall of the fountain of the coating machine. The supply system as thus provided is entirely closed to the atmosphere and suitable means such as a check valve in the pump is provided for maintaining the pipe 90 filled with coating material at all times. The coating material is thus introduced into the coating apparatus without the loss of any of its volatile content.

15 A means is provided for automatically starting the pump 88 to effect the introduction of a fresh supply of the coating material into the fountain 20 of the coating apparatus and for automatically terminating the operation of the pump when the predetermined limited quantity of coating material has been supplied to the fountain. Referring to Figs. 2, 3 and 4 a float chamber 95 is mounted on the rear side of the machine and communicates with the interior of the fountain 20 through an opening 96 provided in the wall portions of the fountain. A cork float 97 is mounted on one end of a lever arm 98 and is adapted to rise and fall with the level of the coating fluid contained within the fountain 20. The lever 98 is pivotally mounted on the wall of the float chamber as indicated at 99 and is provided with an arm 100 operatively connected to an axially slid able plunger 101. A pair of spaced pawls 102 and 103 are adjustably mounted on the plunger 101 and provide for actuating a tiltable mercury switch 104 in accordance with the movement of float 97. The contacts of the mercury switch 104 are connected in the control circuit 105 for the motor 89 as is diagrammatically indicated in Fig. 1 and provide for effecting operation of the motor when the contacts are

closed and for terminating the motor operation when the contacts are open.

The pawl 103 is adjusted on the plunger 101 to a position such that when the level of the coating material within the fountain has dropped to substantially the lowermost portion of the press roll 12 the pawl will have engaged the mercury switch 104 and tilted it to an angle sufficient to close the switch contacts. The electric motor 89 and pump 88 are thus caused to operate to effect the supplying of a fresh quantity of the coating material to the fountain 20. As the level of the coating material in the fountain rises the float 97 rises with it and when the desired predetermined limited quantity of the material has been introduced into the fountain the pawl 102 engages the mercury switch 104 and tilts the switch to effect the opening of its contacts. The operation of the motor 89 and pump 88 is thus terminated and no further fluid is supplied to the fountain until the pawl 103 again engages the switch to effect a closing of its contacts. By adjusting the positioning of the upper pawl 102 relative to the mercury switch 104 the quantity of coating material which is supplied to the fountain during the operation of the pump may be readily controlled. As shown the bottom wall 106 of the float chamber preferably slopes downwardly toward the application roll so as to facilitate complete drainage of the coating material from the chamber during each cycle of operation and avoiding its collection in pockets.

An apparatus is thus provided which maintains continuous control over the volatile content and the viscosity of the coating material from the time that it is received within the large supply tank 85 until after it has been applied to the paper web by the coating machine. Thus a quantity of the coating material having a predetermined volatile content and viscosity is pumped from the supply tank and introduced into the fountain tank 20 of the coating machine. The front and rear cover members 34 and 42 maintain the fountain substantially closed to atmospheric air and thus provide for maintaining the coating material substantially free from contact with the atmospheric air. The front cover member 34, furthermore, extends upwardly above the plane of the nip of the rolls and thus maintains the coating material substantially free from contact with atmospheric air during the time that it is being fed upwardly on the surface of the lower roll 12 and is being applied to the paper web at the nip of the press rolls. An equilibrium condition is thus established within the interior of the fountain and evaporation of the volatiles is substantially avoided until after the coating material has been applied to the paper web. A surface coating of highly uniform characteristics is thus applied to the web under conditions of predetermined controlled substantially constant viscosity.

Evaporation of the volatiles of the coating material is further controlled by the control mechanism for the supply source which provides for introducing only such quantity of the coating material as will be applied to the paper web within a predetermined period of time and for supplying a fresh quantity of the coating material only when substantially all of the predetermined quantity previously supplied has been applied to the paper web. By thus controlling the quantity of coating material introduced into the fountain during each operation of the supply

means the time during which any of the coating material might come into contact with atmospheric air, such as air which might leak around the edges of the inwardly extending flaps 38 and 44, is limited to a time in which there will be substantially no evaporation of the volatiles from the coating material. In practice satisfactory results with a lacquer coating have been obtained where the supply mechanism is adjusted to introduce only such quantity of the coating material as will be applied to the paper web in a period of six to eight minutes.

At the end of each supply cycle a small body of the coating material will remain in the bottom of the fountain. The quantity of the coating material which remains constitutes only a relatively small proportion, about one-fourth, of the quantity of coating material which the fountain contains following each period of supply, since the bottom of the fountain is of arcuate shape and is positioned relatively close to the outer surface of the press roll. Upon the introduction of a fresh quantity of the coating material at the rear of the machine adjacent each end thereof and above the level of the coating material remaining in the fountain, this body of remaining material is washed from the bottom of the fountain into a position where it will be picked up by the roll 12 and be applied to the paper web, the rotary motion of the roll 12 assisting in this action of the freshly introduced material. The accumulation of a quantity of old coating material in a dominant pool at the bottom of the fountain is thus avoided and only relatively fresh material is contained in the fountain at all times. At the end of a coating operation the remaining fluid is drained from the coating machine by means of a nipple 107 positioned centrally of the fountain 20. A cap 108 threads on the nipple 107 and normally prevents the escape of the coating material therethrough.

The adjustable doctor blades 60 at the forward side of the coating machine are so regulated that only as much of the coating material is carried to the nip of the rolls as is being used out of the nip, thus assuring that the coating material will not accumulate in the nip of the press rolls and that only fresh material will be applied to the paper web. A complete control over the viscosity of the coating material is thus maintained and the coating material having a predetermined constant viscosity spreads out uniformly across the entire width of the paper web at the nip of the rolls and is applied as a film of constant uniform density on the web.

As mentioned above a marked economy in the use of the coating material is also afforded by the present invention. Thus by controlling the viscosity of the coating material to effect the application of a material having predetermined controlled viscosity at the nip of the press rolls and throughout the applying operation a substantial increase in the amount of coverage that can be obtained with a given quantity of the coating material is effected and with such controlled viscosity a predetermined desired coverage can be obtained by controlling the pressure that is exerted on the web by the press rolls. For example using only the weight of the top press roll which gave a pressure of approximately 25 pounds per lineal inch of nip, coverages up to 2960 square feet per gallon of lacquer were secured, and when loaded by additional weights to a pressure of 60 pounds per inch, an increase in

covering power up to 3925 square feet was obtained. A product having a uniform homogeneous surfacing of the desired thickness both transversely and lengthwise of the web is thus provided, it being possible to secure commercially such uniform application of the coating material with coverages as high as 3500-4000 square feet per gallon of the coating material while still providing a surface coating of adequate strength and greaseproof characteristics.

While the process, apparatus and product herein described constitute preferred embodiments of the invention, it is to be understood that the invention is not limited to this precise process, apparatus and product, and that changes may be made therein without departing from the scope of the invention which is defined in the appended claims.

What is claimed is:

1. An apparatus of the character described for applying a surface coating material having a volatile constituent to a web of paper material comprising a fountain for receiving a quantity of said coating material, means for continuously feeding coating material from said fountain toward said paper web and for applying said coating material under predetermined pressure as a thin film on the surface of said paper web, means for controlling the evaporation of said volatile constituent to thereby provide for applying a surface coating substantially uniform transversely and lengthwise of the paper web including supply means for introducing said coating material into said fountain, and means for controlling the operation of said supply means to effect the introduction of only such quantity of the coating material as will be applied to said paper web within a predetermined limited period of time.

2. An apparatus of the character described for applying a surface coating material having a volatile constituent to a web of paper material comprising a container for receiving a quantity of said coating material, means for continuously feeding coating material from said container toward said paper web and for applying said coating material as a thin film on the surface of said paper web, means for controlling the evaporation of said volatile constituent to thereby provide for applying a uniform surface coating including supply means for intermittently introducing said coating material into said container, and means for controlling the operation of said supply means to effect the introduction of only a predetermined limited quantity of the coating material into said container during each operation of the supply means and to effect a subsequent operation of said supply means only after substantially all of said predetermined quantity of the coating material has been applied to said web.

3. An apparatus of the character described for applying a surface coating material having a volatile constituent to a web of paper material comprising a fountain for receiving a quantity of said coating material, said fountain having an arcuate shaped lower wall, an application roll dipping within said fountain and closely approaching said arcuate wall for continuously feeding coating material from said fountain towards said paper web and for applying said coating material as a thin film on the surface of said paper web, means for controlling the evaporation of said volatile constituent to thereby provide for applying a uniform surface coating under conditions of predetermined controlled

viscosity including means for maintaining said coating material substantially free from contact with atmospheric air while in said fountain and during said feeding and applying operations, and means for supplying predetermined controlled quantities of said coating material to said fountain, on the downwardly moving side of said roll and above the level of the coating material in said fountain to flush out and progressively utilize the material remaining therein.

4. An apparatus of the character described for applying a surface coating material having a volatile constituent to a web of paper material comprising a container for receiving a quantity of said coating material, means for continuously feeding coating material from said container towards said paper web and for applying said coating material as a thin film on the surface of said paper web, means for controlling the evaporation of said volatile constituent to thereby provide for applying a uniform surface coating under conditions of predetermined viscosity including means for maintaining said coating material substantially free from contact with atmospheric air while in said container and during said feeding and applying operations, supply means for intermittently introducing said coating material into said container in such manner as to wash any remaining quantity of the coating material from the bottom of said container and to provide for its application to said paper web, and means for controlling the operation of said supply means to effect the introduction of only such quantity of the coating material as will be applied to said paper web within a predetermined limited period of time during each operation of the supply means and to effect subsequent operation of said supply means only after substantially all of said predetermined quantity of the coating material has been applied to said web.

5. An apparatus of the character described for applying a surface coating material having a volatile constituent to a web of paper material comprising a roller for applying said coating material to said paper web, a fountain tank for receiving a quantity of said coating material and applying the same to the outer surface of said roller, said fountain tank having a lower arcuate wall spaced relatively close to the peripheral surface of said roller, means for supplying fresh coating material to said fountain tank to displace that remaining therein and to cause progressive feeding of substantially the entire quantity thereof into contact with the surface of said roller and means including a pair of cover members mounted on the upper portions of said fountain tank and extending in overhanging relation with respect to said roller for substantially closing the interior of said tank from contact with atmospheric air to thereby avoid substantial evaporation of said volatile constituent of the coating material and provide for the uniform application of a coating to said web of paper.

6. An apparatus of the character described for applying a surface coating material having a volatile constituent to a web of paper material comprising a roller for applying said coating material to said paper web, a fountain tank for receiving a quantity of said coating material and applying the same to the outer surface of said roll, means including a plurality of spaced-apart doctor blades arranged to engage the surface of said roller and a plurality of adjustable doctor blades positioned intermediate said spaced blades and mounted for adjustment towards and away

from said roller for controlling the quantity of coating material carried by said roller to said paper web, and means including a pair of cover members mounted on the upper portions of said fountain tank and extending in overhanging relation with respect to said roller for substantially closing the interior of said tank from contact with atmospheric air to thereby avoid substantial evaporation of said volatile constituent of the coating material.

7. An apparatus of the character described for applying a surface coating material having a volatile constituent to a web of paper material comprising a roller for applying said coating material to said paper web, a fountain tank for receiving a quantity of said coating material and applying the same to the outer surface of said roll, said fountain tank having a curved bottom wall arranged substantially concentric with the axis of said roll and positioned relatively close to the periphery of the roll, a float chamber communicating with said fountain tank at the bottom portion thereof, means including a float received within said float chamber for controlling the introduction of said coating material into said fountain tank, and means including a pair of cover members mounted on the upper portion of said fountain tank and extending in overhanging relation with respect to said roll for substantially closing the interior of said fountain from contact with atmospheric air to thereby avoid substantial evaporation of said volatile constituent of the coating material.

8. An apparatus of the character described for applying a surface coating material having a volatile constituent to a web of paper material comprising a roller for applying said coating material to said paper web, a fountain tank for receiving a quantity of said coating material and applying the same to the outer surface of said roll, said fountain tank having a curved bottom wall arranged substantially concentric with the axis of said roll and positioned relatively close to the periphery of the roll, means including a pair of inlets arranged in the rear wall of said fountain tank adjacent the ends of said roll and positioned above the level of the lowermost portion of the roller for introducing fresh quantities of said coating material into the interior of said fountain tank, and means including a pair of cover members mounted on the upper portion of said fountain tank and extending in overhanging relation with respect to said roll for substantially closing the interior of said fountain from contact with atmospheric air to thereby avoid substantial evaporation of said volatile constituent of the coating material.

9. An apparatus of the character described for applying a surface coating material having a volatile constituent to a web of paper material comprising a pair of rollers adapted to receive said web of paper material within the nip thereof, a fountain for receiving said coating material and applying the same to the surface of one of said rollers, doctor means for controlling the quantity of coating material carried by said roller to the paper web at said nip, and means for maintaining the viscosity of the coating material substantially constant within said fountain and at said nip including means substantially closing the interior of said fountain and the surface applying side of said nip to contact with atmospheric air to thereby avoid substantial evaporation of said volatile constituent of the coating material, and means for controlling the

introduction of coating material into said fountain to provide for supplying only predetermined limited quantities of the coating material therein and for maintaining substantially all of the coating material within the fountain in a relatively fresh condition having a substantially constant volatile content.

10. An apparatus of the character described for applying a surface coating material having a volatile constituent to a web of paper material comprising a pair of vertically arranged press rolls adapted to receive said paper web within the nip thereof, a fountain tank for receiving a quantity of said coating material and applying the same to the outer surface of the lower press roll, said fountain tank having a curved bottom portion arranged substantially concentric with the axis of said lower roll and positioned relatively close to the periphery of the roll, doctor means carried by said tank adjacent the forward side of said apparatus for controlling the quantity of coating material carried by said lower roll to said paper web, means including a pair of cover members mounted on said fountain tank at the front and rear sides of said apparatus and extending in overhanging relation with respect to said lower roller for substantially closing the interior of said fountain from contact with atmospheric air, said front cover member extending upwardly beyond a horizontal plane passing through the nip of said press rolls and to a position closely adjacent the periphery of the upper roll to thereby substantially close said nip at the forward side of the apparatus from contact with atmospheric air, and doctor means adjustable longitudinally of said press rolls adjacent each end thereof and extending in overhanging relation with respect to the lower press roll at the rear side of said apparatus for scraping coating material from portions of said upper roll which extend outwardly beyond the side edges of said paper web.

11. In a process of the character described for applying a surface coating material having a volatile constituent to a web of paper material, the steps which comprise intermittently introducing said surface coating material into a feeding zone, continuously feeding the coating material from said feeding zone toward said paper web and applying the coating material as a thin film to the surface of the paper web, maintaining the coating material substantially free from contact with atmospheric air while in said feeding zone and during said feeding and applying operations to thereby avoid substantial evaporation of said volatile constituent and provide for applying a uniform surface coating, controlling the supplying of the coating material into said feeding zone to introduce only such predetermined quantity of the coating material as will be applied to the paper web within a predetermined limited period of time, and effecting subsequent introduction of the coating material into said feeding zone only after substantially all of said predetermined quantity of coating material previously introduced has been applied to the paper web, and in an amount in excess of the quantity of coating material remaining in said feeding zone.

12. In a process of the character described for applying a surface coating material having a volatile constituent to a web of paper material, the steps which comprise intermittently introducing said surface coating material into a feeding zone, continuously feeding the coating material from said feeding zone toward said paper

web, applying the coating material as a thin film to the surface of the paper web, maintaining the coating material substantially free from contact with atmospheric air while in said feeding zone and during said feeding and applying operations to thereby avoid substantial evaporation of said volatile constituent and provide for applying a uniform surface coating, controlling the supplying of the coating material into said feeding zone to introduce only such predetermined quantity of the coating material as will be applied to the paper web within a predetermined limited period of time, effecting subsequent introduction of the coating material into said feeding zone only after substantially all of said predetermined quantity of coating material previously introduced has been applied to the paper web, and effecting the introduction of the coating material into said feeding zone in such manner as to wash any remaining quantity of the coating material from the bottom of said zone and to provide for its application to said paper web.

13. A product of the character described comprising a web of paper material having a uniform, homogeneous, greaseproof surface coating film of nitrocellulose material of predetermined substantially constant thickness and density both transversely and lengthwise of the web, said coating film being substantially impervious in a thin film spread to provide a coverage of up to 3500 to 4000 square feet per gallon of the coating material, said product being further characterized in the surface coating being applied to the paper web under predetermined substantially uniform controlled conditions of viscosity and volatile content.

14. An apparatus of the character described for applying a surface coating material having a volatile constituent to a web of paper material comprising a fountain for receiving a quantity of said coating material, a float chamber in direct communication with said fountain and having its bottom wall sloping downwardly to discharge material therein substantially completely into said fountain, a pair of nip rolls through which the web is passed, the lower nip roll dipping within said fountain and picking up a film of coating material on its surface to be carried upwardly into transferring relation with the web of paper, means for regulating the quantity of coating material carried by said roll into contact with said web, and means for controlling the evaporation of said volatile constituent and for maintaining said coating material substantially

5 free from contact with atmospheric air during the time that it is within said fountain and upon the surface of said roll to thereby provide for applying a uniform surface coating of said material to the web of paper.

15. In a process of the character described for applying a surface coating material having a volatile constituent to a traveling web of paper material, the steps which comprise supplying the 10 coating material to a feeding zone for receiving a quantity thereof, picking up a film of said coating material and transferring such film to said traveling web, controlling the evaporation of said volatile constituent and maintaining said coating material substantially free from contact with atmospheric air during the time it is within said feeding zone and being picked up and transferred to said traveling web of paper to thereby provide for applying a uniform surface coating to the web of paper, and supplying additional quantities of coating material to said feeding zone as the material is withdrawn therefrom in excess of the quantity remaining therein and in such manner as to flush the remaining material toward the point where it is picked up for transfer to said web.

16. An apparatus of the character described for applying a surface coating material having a volatile constituent to a web of paper material comprising a roll for applying said coating material to said paper web, a fountain for receiving said coating material and applying the same to the outer surface of said roll, means for maintaining the viscosity of the coating material substantially constant within said fountain and on the surface of said applying roll including means substantially closing the interior of said fountain and the surface applying side of said roll to contact with atmospheric air to thereby avoid substantial evaporation of said volatile constituent of said coating material, means for introducing fresh supplies of said coating material into said fountain to replace material withdrawn therefrom by said roll, and means for controlling said introducing means to provide for introducing a fresh supply of said coating material after the major quantity thereof in said fountain has been withdrawn and in a quantity greater than the quantity of coating remaining in said fountain to thereby maintain substantially all the coating material within said fountain in a relatively fresh condition having a substantially constant volatile content.
